Crane Co., New York, N.Y.

Filed Apr. 16, 1973, Ser. No. 351,698

Term of patent 14 years

Int. Cl. D23—02

U.S. Cl. D23—55

Fig. 1.

Fig. 2.

FIG. 1 is a front perspective view of a combined bathtub and grab rail showing my new design;

FIG. 2 is a top plan view thereof;

FIG. 3 is a side elevation view thereof;

FIG. 4 is a sectional view taken along line 4—4 of FIG. 2; and,

FIG. 5 is a sectional view taken along lines 5—5 of FIG. 2.

The characteristic feature of my invention resides in the particular sloping front trim panel and grab bar, as shown in FIGS. 1, 2 and 4.

I claim:

The ornamental design for the combined bathtub and grab rail, substantially as shown and described.
